Specification of Letters Patent. Patented July 13, 1915.

Application filed November 22, 1912. Serial No. 732,885.

To all whom it may concern:

Be it known that I, DETLEF ANDRES, a subject of the German Emperor, and a resident of Kiel-Gaarden, Germany, have invented a new and useful Improvement in Torches, of which the following is a specification.

My invention refers to cutting and welding devices for use under water. An apparatus having a diving bell to enable a flame to be obtained under water has been used before, but the water absorbs so much of the produced heat that the body to be cut or welded under the water surface could not be heated sufficiently for the autogenous welding or cutting.

In the accompanying drawing the invention is represented in Figure 1 in a vertical cross-section, Fig. 2 is a horizontal cross-section through the upper part and Fig. 3 is a cross-section on line *a*—*b* of Fig. 1.

The novelty consists in the formation of the chamber *f* acting as diving bell, which is situated in front of the nozzle *e*. The bottom of the bell is covered by a perforated sliding cover *g* which can slide in the groove of the part *g*. After the thin flame is ignited while the device is above the water level the slide *g* is closed as represented in the drawing and the device can now be brought under the level of the water. The combustion gases escape through the opening *h* which is connected with a hose (not seen in the drawing) and through the perforation of cover *g* thereby preventing the entering of water. The hose opening *h* reaches the open air above the water and is provided with a throttling device in order to prevent the water entering the diving bell *f*. The device now is pressed against the iron body under the water surface and the slide *g* is opened and the heating pipe *i* is brought into action. The pressure of the gases in the chamber *f* is raised sufficiently high to keep the iron which is in front of the under opening therefor free from water so that the iron is heated to melting point and can be cut or welded by the suitable action of nozzle *e*.

In order to counterbalance the pressure of the water at depths up to 60 meters, a tube *k* having a plurality of exits arranged around the mouth of chamber *f* for compressed air is provided. In order to counterbalance the pressure of the compressed air which will tend to force the apparatus away from the work the apparatus must be pressed with greater force against the work by hand or any other means, according to the depth the apparatus is working in the water. The ignition of the thin flame can also be effected by an electric current.

I claim:

1. An autogenous cutting and welding torch having a nozzle through which gas and combustion air are supplied, a diving bell arranged in front of said nozzle, said bell having means to permit the escape of the products of combustion, a cover for said bell arranged to be removed from the mouth of the bell when said bell is placed in operating position, and means to displace water from around the mouth of the bell when in said operative position.

2. An autogenous cutting and welding torch having a nozzle through which gas and combustion air are supplied, a diving bell arranged in front of said nozzle, said bell having means to permit the escape of the products of combustion, a cover for said bell arranged to be removed from the mouth of the bell when said bell is placed in operating position, and means to supply compressed air around the periphery of said bell to prevent the entrance of water thereto.

3. An autogenous cutting and welding torch having a nozzle, a diving bell arranged in front of the nozzle, said diving bell having a channel for the exit of gases of combustion, a perforated sliding cover for the bell, and a tube having a plurality of exits arranged around the mouth of the bell whereby compressed air may be supplied about the work.

4. An autogenous cutting and welding torch having a diving bell, a nozzle discharging into said bell arranged to main-

tain a water dispelling pressure within said bell to prevent the entrance of water thereto when in operation, said bell provided with means to permit the escape of products of combustion, a plate covering the mouth of the bell and removable from said mouth when operating, and means to peripherally

supply air to said bell to dispel water from around the work.

DETLEF ANDRES.
